UNITED STATES PATENT OFFICE

AUGUST DLOUHY, OF WALLINGFORD, CONNECTICUT, ASSIGNOR TO H. L. JUDD COMPANY, INC., OF WALLINGFORD, CONNECTICUT, A CORPORATION OF DELAWARE

DESIGN FOR A CRANE

Application filed November 23, 1931. Serial No. 41,831. Term of patent 7 years.

To all whom it may concern:

Be it known that I, AUGUST DLOUHY, a citizen of the United States, residing at Wallingford, in the county of New Haven and State of Connecticut, have invented a new, original, and ornamental Design for a Crane, of which the following is a specification, reference being had to the accompanying drawing forming part thereof, in which—

The figure is a perspective view of a crane.

I claim:

The ornamental design for a crane, substantially as shown.

AUGUST DLOUHY.
